United States Patent Office.

DANIEL A. HALL AND DAVID GARRISON, OF PHILADELPHIA, PENNSYLVANIA, ASSIGNORS TO SWAN & CLARK, OF SAME PLACE.

Design No. 4,603, dated January 24, 1871.

DESIGN FOR BOXES FOR THE TOPS OF BUREAUS.

The Schedule referred to in these Letters Patent and making part of the same.

To all whom it may concern:

Be it known that we, DANIEL A. HALL and DAVID GARRISON, of the city of Philadelphia, and State of Pennsylvania, have invented or produced a new and original Design for Boxes for the Tops of Bureaus; and we do hereby declare the following to be a full, clear, and exact description of the same, reference being had to the accompanying drawing making a part of this specification, in which—

Figure 1 represents a perspective view of one of the said boxes, showing its form and ornamentation;

Figure 2 represents a top plan of the same; and Figure 3 represents a vertical section thereof.

This design consists—

First, in the shape or form of the box; and Secondly, in the ornamentation thereof, as shown in the accompanying drawing.

The afterpart A of the box is made of a rectangular form.

The cover B, in its circular direction, is composed of a series of *a b c*, which are reversed in the order mentioned, those *a b* being of shorter and that, *c*, of longer radii.

Where these curves or circles joint, the radial line is distinctly shown at *d*.

The front edge of the lid has a molding, *e*, worked upon it, of the "ogee" order—a series of reversed curved lines.

The lower outer edge of the box *c* is ornamented with a series of leaf-shaped figures, *f g*, the larger ones *g* overlying the shorter ones *f*, and projecting, as seen in fig. 3.

The figures *f g*, instead of terminating in a point, may terminate in small balls or hemispheres *i*.

Having thus fully shown and described our design, What we claim is—

1. The shape or form of the box, as herein represented.
2. The ornamentation on the box, as described and shown.

DANIEL A. HALL.
DAVID GARRISON.
